UNITED STATES PATENT OFFICE.

OTTO HOEFS, OF ALVIN, TEXAS.

CANAL OR DITCH DIGGING MACHINE.

SPECIFICATION forming part of Letters Patent No. 514,850, dated August 20, 1895.

Application filed April 22, 1895. Serial No. 546,724. (No model.)

To all whom it may concern:

Be it known that I, OTTO HOEFS, a citizen of the United States, residing at Alvin, in the county of Brazoria and State of Texas, have 5 invented certain new and useful Improvements in Subterranean Canal or Ditch Digging Machines; and I do hereby declare the following to be a full, clear, and exact description of the invention, such as will enable 10 others skilled in the art to which it appertains to make and use the same.

My invention relates to improvements in machines for boring ditches or tunnels; and it consists, essentially, in the combination of a 15 carriage and means for drawing the same over the ground, and a boring-tool suspended beneath the said carriage and adapted to bore into the ground, either at an inclination to the surface or parallel thereto; and the said invention also consists in certain means for 20 varying the angle at which the boring-tool operates, in novel mechanism for tilting the framework of the carriage to which the boring-tool is rigidly attached, in novel mechanism 25 for rotating the boring-tool, and in certain other novel parts and arrangements thereof, and in certain novel combinations, which will be hereinafter described and claimed.

Reference is had to the accompanying drawings, in which the same parts are indicated by 30 the same letters throughout the several views.

Figure 1 represents a side elevation of the machine, parts being broken away. Fig. 2 represents a plan view of the device shown in 35 Fig. 1. Fig. 3 represents a section along the line 3 3 of Fig. 2 and looking toward the top of the sheet relative to the position of the letters. Fig. 4 represents a section along the line 4 4 of Fig. 2 and looking to the left. Fig. 5 represents a section along the line 5 5 of Fig. 2, showing the details of the mechanism for 40 rotating the boring-tool. Fig. 6 represents a section along the line 6 6 of Fig. 5. Fig. 7 represents a detail view of the frame detached 45 from the vehicle, and illustrates the method of varying the inclination of the frame with regard to the surface of the ground. Fig. 8 represents a section along the line 8 8 of Fig. 7 through one side only of the frame. Fig. 9 50 is an elevation, partly in section, along the line 9 9 of Fig. 10 and looking to the left, and shows the exterior of one of the hubs of the

driving and supporting wheels after its cap has been removed. Fig. 10 represents a section along the line 10 10 of Fig. 9, and also 55 shows a section through the cap, which is then placed on the hub.

The frame on which all the various parts are mounted consists of two end frames A and A', constructed in any suitable way, and connected together by the arched pieces A², made of metal and of sufficient strength, which project upward above the two end frames, and the inverted arch-shaped pieces A³, of similar construction, which are connected to the bottom of the said end frames, and these metal yokes or arch-shaped pieces form a rigid connection between the two end frames, and leave ample room for the said frames to be raised or lowered vertically relative to the axle C, on 65 which wheels B are journaled. These wheels B are provided with hubs B', which are held, the one between the set-collar C² and the cap C' on the one side of the vehicle, and the other between the hub of the sprocket-wheel L³ and a 70 similar cap C' on the other side of the vehicle. The said hub is connected to the axle C and turns the same when the vehicle is drawn forward by means of the pawls c², which engage in the circular rack b' on the interior of 75 the hub B', as shown in Figs. 9 and 10. These pawls c² are pivoted on the pins c' mounted in the cap C', which cap is held by the set-screw c fast on the axle C. It will be seen by 80 an inspection of Fig. 10 that these pawls will only operate when the wheel is turning in the direction of the arrow shown in Fig. 9, which indicates the direction of motion of the wheel when the vehicle is being drawn forward. When the vehicle is being backed, 85 the pawls c² will slide over the rack b', and thus the axle will not be turned when the vehicle is being moved backward. Since the axle imparts its motion to the boring-tool, this function of the pawls c² and hub B' is 90 important. The two wheels are connected to the axle in the same way, although only one has been described as so connected.

The axle C passes through the arched yokes A² and A³, and is journaled in bearings d in 100 the two arms D, provided with sector-arms D', having racks d'. These arms D are pivoted on the wrist-plates E, which are secured to the frame A, as shown in Fig. 8. For conven-

ience in mounting the arms D on the said wrist-plates they are preferably provided with a cap-piece D⁰, bolted to the main body of the arm by bolts d⁰, as shown in Fig. 7; but this 5 particular method of mounting the arm on the wrist-plate is immaterial and may be varied at will. The rack d', on the opposite end of the pivoted arm D, meshes in a pinion F, fast on the transverse shaft F', which shaft 10 carries one of said pinions near either end thereof, which mesh in the corresponding racks d', as shown in Fig. 4. Mounted on this shaft F' is the beveled gear-wheel F², which meshes in the corresponding gear- 15 wheel F³, mounted on the vertical shaft F⁴, and revolved by the hand-wheel F⁵. Thus it will be seen that by turning this hand-wheel F⁵ to the right or left the pinions will cause the pivoted arms D to swing about their pivots; but 20 since these arms are supported on the axle at the bearings d the effect of turning the hand-wheel F⁵ will be to raise or lower the main body of the frame relative to the axle, while at the same time the frame will be given a 25 slight inclination out of the horizontal.

If the pinions F' be situated at very nearly the center of gravity of the machine the tendency of the hand-wheel F⁵ will be to raise the body of the machine vertically, or to lower it 30 vertically, while the desired inclination may be imparted by mechanism shown in Fig. 3, and which will be hereinafter more fully described.

In order to lock the machine at the desired 35 elevation or dépression, a spring-pawl G is provided, which normally engages a ratchet-wheel K on the shaft F'. This spring-pawl slides in guides g fast to the framework A, and is connected by means of the connecting- 40 rod g' and crank g² to the rock-shaft g³, having the arms g⁴ connected by the rod g⁵ to the treadle g⁶, which is pivoted at g⁷ to the frame A' in easy reach of the driver who occupies the seat A⁰, as shown in Fig. 7.

45 There are three seats provided on the machine, two indicated by A⁰ on the main body of the machine, and the third indicated by A⁰¹, mounted on the push-beam A⁸, which projects from the rear of the machine.

50 The boring-tool H is mounted in front of and near the lower extremity of a heavy casting, which is flanged at its upper end, as at a⁴, and bolted fast to the lower side of the frame. This casting, indicated by A⁴, is provided with 55 a curved cutting-edge a, adapted to cut through the ground, the surface whereof is indicated by the dotted lines Z Z in Figs. 1, 3, and 4. This casting is connected to the tongue A⁷ by means of the rod a⁵, which passes 60 over the strut A⁵ and is connected to the pivot of the tongue A⁷, which pivot is represented by A⁶ in Fig. 3. To the back of this casting and connected thereto by the plates a⁸ the push-beam A⁸ is pivoted, which beam is sup- 65 ported on the pair of small wheels B⁴ connected to the beam A⁸ by the bearings a⁸.

These wheels are adapted to span the trench made by the knife-edge a. Cross-trees A¹¹ are mounted on the tongue A⁷ and on the push-beam A⁸, adapted each to be drawn by four 70 horses, as indicated in Fig. 2. It will be seen by an inspection of Figs. 1 and 3 that the draft from the tongue and the pushing strain from the push-beam A⁸ are both applied directly to the casting A⁴, and thus the strain on the 75 frame is largely relieved.

The boring-tool H is preferably in the form of a gimlet, as at h, and is provided with a shoulder h', fitting over a corresponding shoulder a⁹ in the circular bottom piece of the casting A⁴. This bottom piece is provided with a chamber a', in which are mounted the gear-wheel H², which is fast on the shaft H', rigidly attached to the boring-tool H, and the gear-wheel H³, fast on the vertical shaft H⁴, 85 which passes through the cylindrical chamber a⁹ in the casting A⁴, and carries at its upper end a gear-wheel H⁵ meshing in the gear-wheel K, which is mounted on the transverse shaft K', carrying the sprocket-wheel K², as 90 shown most clearly in Figs. 6 and 2. This sprocket-wheel K² meshes in the chain L, which meshes in the sprocket-wheel L', fast on the shaft L², which shaft carries a second sprocket-wheel L³, connected by the chain L⁴ 95 to the sprocket-wheel L⁵ on the shaft L⁶, which shaft also carries another sprocket-wheel L⁶, which is driven by the chain L⁷ from the sprocket-wheel L⁸, which is fast on the axle C. Thus it will be seen that the rotation of the 100 axle is transmitted by means of these various sprocket-wheels and chains to the shaft K', which transmits its motion to the boring-tool H, causing the latter to revolve as the vehicle moves forward.

105 Idlers M, M', and M² may be provided for the purpose of guiding and keeping taut the various chains, but these are not essential and may be omitted if desired.

In order to stop the revolution of the boring-tool when the vehicle is moving ahead, should this be desired—as, for instance, in moving the vehicle about from one place to another—I provide any suitable clutch-coupling, indicated by N. (See Figs. 2 and 3.) This clutch-coupling is operated by the hand-lever N', connecting-rod N², and clutch-arm N³; but the details of the clutch mechanism are not a part of my invention, and any suitable clutch may be provided. It will be seen that when 110 the clutch N is uncoupled the shaft L⁶ will revolve in the sprocket-wheel L⁵, which is loosely mounted thereon, and the sprocket-chain L⁴ and mechanism operated thereby 115 will be thrown out of action.

120 P represents a revolving colter or knife adapted to split open the surface of the ground in front of the casting A⁴, and thus to assist the same in breaking through the surface of the soil.

125 The frame carrying the boring-tool is tilted so as to cause the boring-tool either to enter

the ground, as shown in Fig. 3, or to come out of the ground, as when tilted in the opposite direction by means of the hand-lever Q , which is pivoted at q , and has a handle q^2 provided with a spring-pawl arrangement Q' , adapted to engage in the rack R , which rack is in the form of an arc of a circle whose center is q . The lower arm q' of this hand-lever Q is connected, by means of the rod q^3 , to the push-beam A^8 , to which said rod is pivoted, as at q^4 .

The rear end of the casting A^4 is pivoted with grooves or guides s , s' , and s^2 for a movable compressing-plate S , detachably connected, as shown, in the grooves s , to the rear edge of the said casting, and adapted to press down the earth after the said casting passes through the same, forming a closed top to the tunnel formed by the boring-tool H . Any number of the guides for compressor-plates may be provided, arranged at different heights along the rear of the casting A^4 for the purpose of adapting the machine to pressing flat the double ridge that would normally be in the wake 25 of the casting A . In this way the compressor-plate may be adjusted to any depth of boring.

The operation of the device is as follows: The frame is lifted so that the boring-tool shall be about clear of the ground, which can 30 be done by revolving the hand-wheel F^5 , and then the said frame is tilted by means of the hand-lever Q to a position somewhat like that shown in Fig. 3. Then the pawl G is drawn back, allowing the whole weight of the 35 machine to rest on the boring-tool H , and the vehicle is started forward. The boring-tool will bore an inclined hole downward, pressing the earth to either side of it, until the entire boring-tool is below the surface, and the 40 frame A^4 shows that the proper depth for the bottom of the ditch or tunnel has been reached. The boring-tool is then brought to the horizontal position by means of the hand-lever Q , which brings the frame gradually 45 down to the horizontal position and as gradually changing the direction of the line of boring from the inclined to the horizontal. It will, of course, be advisable to change the direction of the line of boring gradually and to 50 start doing so before the maximum desired depth is reached, for it will be somewhat difficult to change the direction of the boring-tool suddenly while it is embedded in the ground. After the boring-tool has reached the desired 55 depth and the frame has been moved into the horizontal position, the said boring-tool will bore an underground tunnel, packing the earth on all sides thereof so hard as in ordinary soils to render the danger of caving in 60 comparatively small. Into this tunnel tiles or pipes may be readily placed, it being only necessary to dig down occasionally from the surface. Should it be desired to cut an open 65 ditch, the upper portion of the walls may be cut away, as by shovels or spades, or in any other convenient way, leaving the bottom of

the boring a hard and well-packed bottom for the ditch. The revolving knife P assists in opening up the soil for the casting A^4 , while the compressing-plate S smooths down the 70 ridges behind the casting A^4 and covers up the crack left in the earth by the said casting as it passes through.

Should it be desired to run the boring-tool toward the surface of the ground, as at the 75 end of the boring, or to avoid an obstacle, it will only be necessary to tilt the frame in the opposite direction from that shown in Fig. 3, and to take as much weight as possible off the boring-tool, as by turning the hand-wheel 80 F^5 in the reverse direction. Thus it will be possible to move the boring-tool upward at an angle, as to avoid a buried log, and then after passing the log to deflect it downward again, as has been hereinbefore described. It will 85 thus be seen that the boring-tool may be caused to bore at an incline downward or at an incline upward to follow a path parallel to the surface of the soil or to follow an undulating path beneath the soil; also, that while 90 the herein-described mechanism enables the operator to vary the vertical position of the boring-tool, the vehicle may be caused to follow any desired path over the surface of the ground, and thus a ditch or tunnel may be 95 cut which would be irregular either in depth or in direction, or both, or which might be straight and of a uniform depth.

Where it is desired to drain bottom land, it is especially desirable to be able to readily 100 dig a crooked ditch which shall be at the desired depth from the surface and shall follow the contour of the land.

It will be obvious that the herein-described apparatus is especially adapted for use in 105 alluvial land or prairie land free from rocks.

It will be obvious that many modifications of the herein-described apparatus might be made which could be used without departing from the spirit of my invention.

While I have shown the vehicle as adapted 110 to be drawn by horses or mules, any suitable motive power may be adopted, such as a portable steam engine, electric motors or the like.

Having thus described my invention, what 115 I claim, and desire to secure by Letters Patent of the United States, is—

1. In a machine of the character described, the combination with a wheeled vehicle and a frame carried thereby, of a boring tool journaled in bearings rigidly attached to said frame, means operated by the motion of said wheels for rotating said tool, means for moving said frame vertically on said vehicle, and for tilting said frame, and means for slicing 120 open the ground above said tool, substantially as described.

2. In a machine of the character described, the combination with a wheeled vehicle and a frame carried thereby, of a gimlet-headed 125 boring tool journaled in bearings rigidly attached to said frame, means operated by the

motion of said wheels for rotating said tool, means for moving said frame vertically on said vehicle, and for tilting said frame, and a compressing plate for smoothing the ground 5 in rear of said tool, substantially as described.

3. In a machine of the character described, the combination with a wheeled vehicle and a frame carried thereby, of a cutting and boring device secured beneath said frame and 10 comprising a metal frame or casting A⁴ provided with a cutting edge a, and the boring tool journaled near the base of and projecting to the front of said casting, substantially as described.

15 4. In a machine of the character described, the combination with a wheeled vehicle and a frame carried thereby, of a cutting and boring device secured beneath said frame and comprising a metal frame or casting A⁴ provided with a cutting edge a, and the boring tool journaled near the base of and projecting to the front of said casting, substantially as described.

20 5. In a machine of the character described, the combination with a wheeled vehicle and a frame carried thereby, of a cutting and boring device secured beneath said frame and comprising a metal frame or casting A⁴ provided with a cutting edge a, and the boring tool journaled near the base of and projecting to the front of said casting, with gearing for revolving the said boring tool mounted on the said casting, substantially as described.

25 5. In a machine of the character described, the combination with a wheeled vehicle and a frame carried thereby, of a cutting and boring device secured beneath said frame and comprising a metal frame or casting A⁴ provided with a cutting edge a, and the boring tool, the gimlet-headed boring tool H, journaled near the base of and projecting to the

front of said casting, substantially as described.

6. In a machine of the character described, 35 the combination with a wheeled vehicle, and a frame carried thereby, of a cutting and boring device secured beneath said frame, and comprising a metal frame or casting A⁴ provided with a cutting edge a, and the boring 40 tool journaled near the base of and projecting to the front of said casting, with gearing for revolving the said boring tool mounted on said casting, substantially as described.

7. In a machine of the character described, 45 the combination with a wheeled vehicle and a frame carried thereby, of a cutting and boring device secured beneath said frame and comprising a metal frame or casting A⁴, provided with a cutting edge a, and the gimlet-headed boring tool H, journaled near the base of and projecting to the front of said casting, with guide grooves along the sides of said casting, with a detachable compressing plate adapted to fit in any one of said guide grooves 50 and to project to the rear of said casting, substantially as described.

In testimony whereof I affix my signature in presence of two witnesses.

OTTO HOEFS.

Witnesses:
